UNITED STATES PATENT OFFICE.

EMIL GOTTFRIED JOHANSON, OF CHICAGO, ILLINOIS, ASSIGNOR TO DAVID H. ROBLIN,
OF CHICAGO, ILLINOIS.

DESIGN FOR A PRISM-GLASS.

50,420.

Specification for Design.

Patented Mar. 6, 1917.

Application filed September 30, 1916. Serial No. 123,186. Term of patent 14 years.

To all whom it may concern:

Be it known that I, EMIL G. JOHANSON, a subject of the King of Sweden, residing at Chicago, in the county of Cook and State of Illinois, have invented a new, original, and ornamental Design for a Prism-Glass, of which the following is a specification, reference being had to the accompanying drawing, in which—

Figure 1 is a plan view of a fragment of the glass embodying the design and Figs. 2

and 3 are cross sections on the lines 2—2 and 3—3, respectively, of Fig. 1.

The drawing shows the design applied to a glass which is flat, but it is to be understood that the design is also applicable to glass which is curved in cross-section.

I claim:

The ornamental design for a prism glass as shown and described.

EMIL GOTTFRIED JOHANSON.
